UNITED STATES PATENT OFFICE

2,660,620

AUTOMATIC TELEPHONE SYSTEM

Fernand Pierre Gohrel, Antony, France, assignor
to International Standard Electric Corporation,
New York, N. Y., a corporation of Delaware

Application September 30, 1950, Serial No. 187,718

Claims priority, application France
October 3, 1949

2 Claims. (Cl. 179—18)

1

In the patent application filed on June 14, 1950, Serial No. 163,072, by Martinus den Hertog et al., for a "Selection system for electrical circuits or equipments," a group selector has been described which comprises, for each connector, in addition to the control magnet of the connector, an additional relay. The details of the selector are shown in the application filed by A. J. Montchausse on January 26, 1950, Serial No. 140,735.

The object of the present invention is, by means of special circuit arrangements, to eliminate the additional connector relay and only to provide a single electro-magnet, in order to ensure the functions of association of the selector to the common control circuit and thus a connection of the input of the selector to the outgoing lines, and to improve the operative conditions.

One of the characteristics of the invention consists in the fact that the input wires of each selector are connected to the common control circuit and that the input wire which is employed to produce the connection is connected to said common control circuit through a winding of the control magnet of the connection.

Another characteristic of the invention consists in the fact that the winding of the control magnet of the connection, inserted in one of the input wires of the selector in the common control circuit, is provided in such a way that it does not cause the attraction of the armature of said control magnet, when the selector is seized, the intensity of the current passing through it not having sufficient value, but it causes the attraction of said armature only when an outgoing line of the selector fulfilling the required conditions, has been found by the common control circuit, means being provided then to modify the intensity of the current in said winding.

Another characteristic of the invention consists in the fact that between the register and the common control circuit, mutual control means are provided such that the control of the connection of the selector to the chosen line, said control being effected by the common control circuit, can only be effected if the register has cut off all the circuits which, at the moment of the connection to the outgoing line, would be capable of causing a false order.

Another characteristic of the invention consists in the fact that a single test wire is provided for each outgoing line of a selector, said wire being employed for electronic hunting, and for the second test made with direct current.

2

This latter arrangement has the particular advantage of engaging the chosen line with respect to an electronic finder as soon as the second test has started, while its busy condition is given, in selectors of the type described in the above mentioned application, only after the complete operation of the selector and the energisation in the next selector of the relay which operates at the time that said selector is seized.

10 The time during which a double test is possible is thus considerably reduced, which has the effect of accelerating selection to a very great extent.

Another characteristic of the invention consists in the fact that means are provided so that the busy condition of the chosen line is maintained by the common control circuit until this busy condition is given by the selector itself at the time of the connection.

15 20 The essential idea of the invention, as also various other characteristics, will become clear from the following description given as a non-limitative example, with reference to the attached drawing, in which only those elements are shown which are necessary for an understanding of the invention. The arrangements shown correspond to a case of a group selector, but they are applicable to the case of a line selector.

25 30 Fig. 1 is a circuit diagram of a portion of a selecting system embodying the invention showing the register and portions of two selectors; and

35 Fig. 2 is a circuit diagram of another portion of the selecting system, showing other selectors and a common control circuit.

In Fig. 1 of the drawing are shown the elements of register *En* seized for the selections and establishment of the connection, said register comprising an electronic comparator *COE*, and.

40 45 Fig. 2, which should be placed at the right of Fig. 1, shows the elements of a selector *S4* associated with a common control circuit *Or* which comprises an electronic finder *CHE*. The common control circuit *Or* is associated with other selectors similar to *S4*.

The contacts *HB* (Fig. 2) are associated with one of the horizontal connection bars of the selector, which is a multiswitch of the cross-bar type, and operated by said bar, and the contacts *H* are associated with the clutch control magnet *H* of said bar.

The line of the calling station *PA* must be put in communication with the line of the wanted station *PD*, through the selectors *S2*, *S3* and *S4*.

50 55 While the communication is being established,

the register *En* (Fig. 1) is connected, through a finder *S1*, successively to the selectors *S2*, *S3* and *S4* in order to check the routing, in accordance, with the general operation described in the patent application, Serial No. 168,072, referred to above and in the application, Serial No. 171,341, filed June 30, 1950, by the same inventor.

It will be assumed that selectors *S2*, *S3* have been routed and that the register is connected to the inputs *a3*, *b3*, *c3*, *d3*, of selector *S4*. The following circuit is completed: earth, make contact *B2* of relay *Br*, winding of *Chr*, wires *b1*, *b2*, and *b3* (Fig. 2), back contact *HB1*, right-hand winding of the clutch control magnet *H* of the selector, 15 winding of relay *Bo'r* and battery. The resistance of relay *Chr*, *Bo'r*, and of magnet *H* are such that relays *Chr* and *Bo'r* are energised in series but the magnet *H* cannot operate its armature. By its make contact *Bo'l*, the relay *Bo'r* completes the circuit of relay *Bor* which is energised through the back contacts *Hrl* of the relay *Hr*, and *Col* of the relay *Cor*. By its contact *Bol*, the relay *Bor* prepares the firing circuit of the tubes *VA* to *VC*. By its contact *Chl* (Fig. 1), relay *Chr* completes the impulse transmitting circuit of amplifier *A1* (Fig. 2) of electronic finder *CHE* to the electronic comparator *COE* (Fig. 1) of register *En*. These impulses are sent in predetermined time units and characterise each line and each group scanned as has been explained in the application, Serial No. 168,072, referred to above. When a line is free, an earth potential is applied to the input point *F* (Fig. 2) in the electronic finder *CHE* of the test wire of said line. This test potential is applied through resistance *R'2*, back contact *H'1*, back contact *HB'6* and the wire *g4*. The contacts *H'1* and *HB'6* are respectively associated with the brake magnet *H'* (Fig. 1) of the scanned selector and with the connecting bar of said selector.

When a free line in the wanted group is scanned, an impulse situated in time *Pdu*, for example, is received in the amplifier *A1* of the electronic finder *CHE* and sent through: back contact *H2*, back contact *HB3*, wire *d3*, *d2* (Fig. 1), *d1*, back contact *Ok1* and make contact *Ch1*, to the electronic comparator *COE*. Said comparator moreover, receives the comparison impulse *Pdu* through the rectifier *Rd*. The coincidence of the impulse received from *CHE* and the comparison impulse causes the transmission of said impulse *Pdu* in the amplifier *A2* and the transformer *T* as has been explained in the patent application, Serial No. 168,072, referred to above.

The impulse received in transformer *T* is transmitted on the one hand to a discharge tube *VS* of *COE*, and, on the other hand, through the circuit: right hand winding *T*, wire *c1*, *c2*, *c3* (Fig. 2), back contact *HB2*, to a series of tubes *VA*, *VB*, *VC* and *VD* of the electronic finder *CHE*.

The tube *VS* is fired, contacts *B1*, and *Ok2* being closed, and the relay *Sir* is energised. Through its contact *Sil*, the relay *Sir* forms the circuit of relay *Otr* which is energised. The tube *VD* (Fig. 2) of *CHE* is fired and applies to the point *M* a sufficient potential to block the input of amplifier *A1* so that no other characteristic impulse can be sent by said amplifier. Moreover, certain of the tubes *VA*, *VB*, *VC* are also fired in accordance with the time unit in which the impulse from the register is received, that is to say, in accordance with the line scanned in

the same time unit. Tubes *VA*, *VB* and *VC* being fired (1 tube *VA*, 1 tube *VB*, 1 tube *VC*) cause the energisation of the routing relays *Oa*, *Ob*, *Oc* as has been explained in the above mentioned patent application; the routing relays comprise a certain number of contacts, the combination of which makes possible the energisation of a magnet such as *Vu* (*Vu'*) which corresponds to the line scanned, and found free. If, for example, a magnet *Vu* is energised, it closes its contacts *Vu1* and *Vu2*. The contact *Vu1* closes the energisation circuit for the relay *Hr* in series with *Vu* and in parallel with the resistance *r'1* through make contact *Oa1* or *Ob1*. Contact *Vu2* causes the following test circuit: earth, resistance *R'2*, back contact *H'1*, back contact *HB'6*, wire *g4*, make contact *Vu2*, point *X* where test wires of the outgoing lines of the selector are reassembled, contact *Hr3* closed; relay *Cor*, back contact *HB4*, wire *a3*, *a2* (Fig. 1), *a1*, back contact *Pel* of relay *Per*, make contact *Ot3* of relay *Otr*, upper winding of relay *Tr* and battery. The relay *Tr* is energised and shunts its upper high resistance winding through its lower low resistance winding in series with the relay *Dtr*, through the make contact *T1* of *Tr*. If two selectors simultaneously seized the same line, two relays *Tr* of the registers temporarily associated would be energised, but as soon as their make contact *T1* was closed, the number of ampere turns in each relay shunted by each other, would not be sufficient to maintain both of them pulled up; as the release of the two relays *Tr* does not take place simultaneously because a very slight deviation of operation always results in the manufacture of two identical relays, the first to fall back opens its contact *T1*, the other is held in the operative position. As soon as the relay *Tr* is energised, the wire *g4* is brought to a negative potential of the feed battery (-48 v.) owing to the fact of the relatively high value of the resistance *R'2* in relation to that of the relays *Dtr*, *Tr*, and *Cor*. The result is that the point *F* (Fig. 2) of input in *CHE* and consequently the point *FM* are set at such a negative potential that all the electronic finders of the other common control circuits serving the selected line will not send impulses when they explore said line, which is immediately made busy.

When the relay *Dtr* (Fig. 1) of the register *En* is energised in series with the low resistance winding of the relay *Tr*, the relay *Cor* (Fig. 2) of the common control circuit *Or* is also energised. By its contact *Co1*, the relay *Cor* opens the circuit of the relay *Bor* which falls back, and which, by the opening of its contact *Bol*, causes the extinction of the tubes *Va*, *Vb*, *Vc*, *Vd*. Through its contact *Co2*, relay *Cor* closes a holding circuit of the relay *Hr* of which the energisation circuit is opened by the release of the relays *Oa* or *Ob*. Through its contact *Co3*, the relay *Cor* holds the amplifier *A1* blocked (at least for the scanning impulses) after the extinction of the tube *VD*.

In the register *En* (Fig. 1), the relay *Dtr*, which is pulled up, opens through its contact *Dt1* the circuit of relay *Otr* which is released. Through the make contact *Dt2* of relay *Dtr* and the back contact *Ot1* of relay *Otr*, energisation circuit of the relay *Okr* is completed. After the release of relay *Otr* and the opening of its make contact *Ot3*, the circuit of relays *Tr* and *Dtr* is completed by the make contact *Dt3* of *Dtr*. Through its make contact *Ok3* the relay *Okr* applies a direct earth to the wire *b1*, *b2*, *b3* (Fig.

2) and, through its contact O_{k1} (Fig. 1), applies the wire $d1$ to earth through the upper low resistance winding of relay Per ; through its back contact O_{k2} , it opens the circuit of the tube VS and of the relay Sir which is released.

Owing to the application of direct earth through O_{k3} to the wire $b1, b2, b3$, the intensity in the circuit of the right hand winding of magnet H (Fig. 2) of the selector is strongly increased and sufficiently so that said magnet H operates its armature causing the engagement of the bar of the selector with the operating bar of the servo-magnet. Through its contact $H1$, the magnet H cuts off resistance $R2$ from the wire $e3$ and substitutes for it the left hand winding of magnet H , thus completing the holding circuit for said magnet H on the battery through the resistance $R1$ of selector $S3$. Through its contact $H2$, the magnet H disconnects wire $d3$ from electronic finder CHE and returns it to the relay Gr which is thus placed in series with the relay Per . The resistances of relay Per and Gr are provided in such a way that only the relay Gr is energised. Through its make contact $G1$, the relay Gr completes the circuit of relay Kr which is energised. The left hand high resistance winding of Gr is then short circuited by the make contact $G2$ of the relay Gr and by the make contact $K2$ of the relay Kr ; owing to this, the current circulating in the upper winding of the relay Per of En , in series with the right hand low resistance winding of Gr , is sufficient to cause the attraction of said relay Per (Fig. 1). By this circuit, the energisation of magnet H and of the relays Gr and Kr is thus controlled.

Through its back contact $Pe1$, the relay Per opens the test circuit, that is to say, the circuit of relays Tr and Dtr which fall back. Through its back contact $Pe2$, relay Per opens the circuit of Okr which falls back, if the relay Sir has already been released, that is to say, if its holding circuit, through its make contact O_{k4} and the make contact S_{i2} of the relay Sir , is open. When the relay Okr has fallen back, the circuit of the upper winding of the relay Per is opened by the contact O_{k1} ; however the relay Per is maintained operated on its lower winding by its make contact $Pe3$ and the make contact $Dt4$ of the relay Dtr , as long as the relay Dtr has not released, in order to maintain the contact $Pe1$ open until the contact $Dt3$ of relay Dtr is open, so as to maintain a cut off on the wire $a1, a2, a3$ during the time of operation of connection of the selector, which can only take place if said wire is open. The busy condition of the selected line is maintained by the contact $K3$ (Fig. 2) of the relay Kr which connects the winding of Cor to battery through a low resistance $r4$.

When the make contact O_{k1} (Fig. 1) of relay Okr is open at En , the relay Gr (Fig. 2) of Or falls back and through its back contact $G1$ and the make contact $K4$ of the relay Kr completes the circuit of the servo-magnet SH which causes the operation of the connecting bars of the selectors. The operating bar of selector $S4$ is

actuated which causes the connection of wires $a3, b3, c3, d3$ to the wires $a4, b4, c4, d4$ and the operation of contacts $HB1, HB2, HB3, HB4$ which cut out connection of selector $S4$ to the common control circuit Or , of the contact $HB5$ which, through resistance $R'1$, applies a negative potential of the battery to the wire $e4$ so as to maintain the seized line busy.

Finally, the servo-magnet SH opens through its contact $Sh1$ the circuit of relay Kr which falls back.

The common control circuit has thus returned to normal and the register is ready to proceed with the next selection.

I claim:

1. In an automatic telephone system a selector switch for setting up a connection between a calling and a called line, said selector switch being of the cross-bar type having input lines, output lines, normally open contact means for connecting said input lines with selected ones of said output lines, and normally closed additional contact means associated with said input lines and controlled by the operation of the switch horizontal connection bars, and a clutch control magnet for each of said connection bars, the combination comprising a control circuit connected to said input lines over said additional contact means, a register, means for connecting said control circuit over said input lines of said selector switch to said register, an electronic comparator in said register, means for setting said comparator to respond to an impulse at a predetermined time position identifying a group of lines of which a free line is to be selected, means in said control circuit for sending impulses over said input lines at a plurality of different time positions representing a free line in the selected group, means in said register responsive to the operation of said comparator for sending an impulse at the time position corresponding to that of the first free line to said control circuit, means in said control circuit for registering the time position of the received impulse from said register, and means controlled by said registering means for operating said clutch control magnet so as to close the outgoing contacts to said first free line and simultaneously open said additional contacts so as to disconnect said control circuit.

2. In an automatic telephone system, the combination, as defined in claim 1, in which there are a plurality of sets of input lines, a set of additional, normally closed contacts, for connecting each set of input lines to the control circuit, and a clutch control magnet for each set of input lines, further comprising an energizing winding on each of said clutch control magnets, and means including a pair of additional contacts of the set associated with a magnet for connecting the energizing winding thereof in series between the associated input line and the control circuit.

FERNAND PIERRE GOHOREL.
